CLAIM

The ornamental design for a display screen with animated graphical user interface, as shown and described.

DESCRIPTION

This invention was made with U.S. government support under Contract No. DK120234, awarded by the National Institutes of Health. The government has certain rights in the invention.

FIG. 1 is a front view of a first image of a first embodiment of a display screen with animated graphical user interface embodying the new design;

FIG. 2 is a front view of a second image thereof;

FIG. 3 is a front view of a third image thereof;

FIG. 4 is a front view of a fourth image thereof; and

FIG. 5 is a front view of a fifth image thereof.

FIG. 5 is a front view of a first image of a second embodiment of a display screen with animated graphical user interface embodying the new design;

FIG. 4 is a front view of a second image thereof;

FIG. 3 is a front view of a third image thereof;

FIG. 2 is a front view of a fourth image thereof; and,

FIG. 1 is a front view of a fifth image thereof.

The broken line showing of a display screen with graphical user interface is included for the purpose of showing portions of the article which form no part of the claim. Solid black portions indicate a contrast in appearance.

The appearance of the transitional image of a first embodiment of the claimed design sequentially transitions between the images shown in FIGS. 1-5. The appearance of the transitional image of a second embodiment of the claimed design sequentially transitions between the images shown in FIGS. 5-1. The process or period in which one image transitions to another image forms no part of the claimed design.
